AUTOMATIC MARKING DEVICE

Gordon L. Rashman, Milwaukee, Wis., assignor
to Rhea Manufacturing Company, Milwaukee,
Wis.

Application September 5, 1936, Serial No. 99,675

9 Claims. (Cl. 164—86)

This invention relates to automatic marking drills, and more particularly to a drill of the type employed to bore through multiple thicknesses of fabric in the manufacture of garments and the like so as to mark uniform points in the various pieces of fabric.

An object of the invention is to provide a device of the type which will enable an operator to bore through a plurality of layers of fabric in a substantially vertical line, thus obtaining a consistently uniform marking of many layers of cloth. Other devices of the type now in use are not accurate because of a lack of means for precision guidance of the same.

Another object of the invention is to provide a drill coupled with electrical devices for terminating its operation immediately upon the deviation of the tool from a perfect vertical alignment.

Another object of the invention is to provide a drill having individual directional electrical switches and means for individual adjustment of the same.

Other and further objects of the invention will appear as the description proceeds, reference being had to the accompanying drawings, in which:

Fig. 1 is a side view in elevation and partly in section of a drill embodying my invention.

Fig. 2 is a view taken on line 2—2 of Fig. 1.

Fig. 3 is a view taken on line 3—3 of Fig. 1.

Fig. 4 is a fragmentary view, partly in section and partly in elevation, showing one of the mercury switches.

Fig. 5 is a wiring plan for the switches and motor utilized in the device.

Referring more particularly to the drawings, the numeral 10 represents the base portion of the device, having the upstanding lugs 11 and 12, to which are secured, by rivets 13 and 14, the tubes 15 and 16. Supported at the top of tubes 15 and 16 is the inverted U-shaped member 17, having the downwardly projecting lugs 18 and 19, securing the same by means of rivets 20 and 21 to the tubes 15 and 16.

Integral with the member 17 and at the top thereof is a collar 22, slidingly retaining a rod 23, having the keyway 24, bordered by the calibrations 25. A key 26, secured interiorly of collar 22 by means of screws 27, engages in keyway 24 and fixes the rod 23 against rotation. The latter is surmounted by an eye 28. At the lower end of rod 23 are the legs 29, to which is attached by means of screws 30 the motor 31, having the shaft 32 and chuck 33, for retention of the conventional drill 34. A guide 35 embraces the tube 15, adja-

cent to the lower end thereof, and has a tongue 36, extending inwardly through a slot 37, in said tube. A coil expansion spring 38, abutting a pin 39, extending transversely and centrally of the tube 15 with its upper end, and the tongue 36 with its lower end, serves to maintain a bushing 40 held in the extension 41 of guide 35, against the material to be drilled.

A switch box 42 contains a plurality of mercury switches 43, 44, 45 and 46, of conventional type, connected in series. Referring to the wiring plan as shown in Fig. 5, the current enters by means of the wire 47 through the main switch 48 and successively through the mercury switches 43, 44, 45 and 46, and through the motor 31 and outwardly by means of wire 49, to complete the circuit. Each of the mercury switches 43, 44, 45 and 46 is mounted on a plate 50 by means of a clip 51. Each plate 50 is pivoted as at 52 of Fig. 4 and adjustable by means of screws 53 and 54. The rod 23 is notched at 55 to receive the stop lever 56, pivoted at 57 of number 17 and linked at 58 with a hand lever 59. A stop-collar 60, having the set screw 61, embraces the rod 23 and may be fixed to prevent the descent of the drill beyond a desired level.

The base 10 carries the hydrostatic levels 62 and 63 for the guidance of the operator of the drill.

In operation, the device is placed with the base against and on the top of a plurality of layers of cloth to be marked. The handle 59 is then gripped to allow descent of the drill 34. The switch 48 is closed and operation of the motor will ensue, providing the drill is kept on a substantially perfectly vertical line. It will readily be seen that even a slight deviation from the vertical will shift the mercury 64 in one or more of the tubes 43, 44, 45 and 46, thus breaking the circuit between the points 65 and 66 to stop the motor 31.

The device is capable of many modifications in structure and design without departing from the spirit of the invention within the scope of the appended claims.

Having thus described my invention, what I claim and desire to secure by Letters Patent of the United States is:—

1. A device of the class described comprising a base, a standard attached to said base having a collar, a vertical rod mounted in said collar, a motor fixed dependingly on said rod, a drill extending downwardly from said motor, a switch box on said standard, mercury switches in said switch box connected with said motor, and means for

adjusting the individual levels of said mercury switches.

2. In a device of the class described, a base, a standard extending upwardly therefrom, a collar

5 integral with said standard, a rod slidably embraced in said collar, a notch in said rod, a manually operable stop engaging said notch, a motor drill depending from said rod, a source of current supply, a plurality of mercury switches

10 connected in series between the current supply and the motor, and a main switch intermediate said source and the mercury switches.

3. In a device of the class described, a base, a standard extending upwardly therefrom, a collar 15 integral with said standard, a rod slidably embraced in said collar, a motor drill depending from said rod, directional levelling mercury switches attached to said standard adjacent said collar and connected with said motor, and means 20 for individual adjustment of said switches.

4. In a device of the class described, a base, a standard fixed thereon, means vertically slidable in said standard, a motor drill fixed dependingly on said slidable means, hydrostatic levels dis- 25 posed at right angles for bidirectional action on said base, and mercury switches for said motor disposed on said standard and actuated by the tilting of the latter.

5. In a device of the class described, a base, a 30 standard fixed thereon, means vertically slidable in said standard, a motor drill fixed dependingly on said slidable means, hydrostatic levels dis- posed at right angles for bidirectional action on

said base, mercury switches for said motor disposed on said standard and actuated by the tilting of the latter, and means for individually adjusting said mercury switches.

6. In a motor-driven drill for vertical use, a 5 current supply for said motor, a quadratic rectangular arrangement of mercury switches in said current supply for automatic shut-off of the current supply to said drill.

7. In a device of the class described, a rotating 10 tool, a motor for operating the tool, an electrical circuit for operating the motor, mercury switches arranged in a plurality of directions in said circuit for interrupting a current therethrough on the deviations of said device from a given desired 15 alignment.

8. In a device of the class described, a rotating 20 tool, a motor for operating the tool, an electrical circuit for operating the motor, mercury switches arranged in a plurality of directions in said circuit for interrupting a current therethrough on the deviations of said device from a given desired alignment, and means for adjusting said mercury switches.

9. In a device of the class described, a rotating 25 tool, a motor for operating the tool, an electrical circuit for operating the motor, mercury switches arranged in a plurality of directions in said circuit for interrupting a current therethrough on the deviations of said device from a given de- 30 sired alignment, and means for individually adjusting said mercury switches.

GORDON L. RASHMAN.
